(57) **CLAIM**

I claim the ornamental design for urinal screen, as shown and described.

DESCRIPTION

FIG. 1 is a top plan view of a urinal screen showing my new design;

FIG. 2 is a bottom plan view thereof;

FIG. 3 is a front elevational view thereof;

FIG. 4 is a rear elevational view thereof;

FIG. 5 is a left-end elevational view thereof; and,

FIG. 6 is a right-end elevational view thereof.

The 48 circles shown in the plain views are through holes. The four, peripheral, substantially rectangular raised planar surfaces shown in FIG. 1 can receive advertisements or other indicia.
